UNITED STATES PATENT OFFICE

2,627,081

ADJUSTABLE SPRING CASTER DOOR SUPPORT

Robert E. Slopa, Chicago, Ill., assignor of one-half
to George W. Slopa, Chicago, Ill.

Application March 3, 1950, Serial No. 147,555

1 Claim. (Cl. 16—44)

1

The invention relates to improvements in door supports, and is particularly concerned with an adjustable door supporting roller and mounting therefor.

Heavy hinged doors, such as for example walk-in refrigerator doors, very often sag regardless of the type of hinges used for mounting the door. It is, therefore, often advisable to install some form of support at the foot of the free edge of the door. Such a support must of necessity include a roller that will travel on the floor during opening and closing of the door. Inasmuch as the floor in the area of the refrigerator opening closed by the door is, or soon becomes, uneven because of excessive wear, the roller mounting preferably is yieldable so as to compensate for such irregularities. It is, therefore, an object of the present invention to provide a novel roller support for a door, which is constructed so as to afford essential yieldability in the roller mounting.

In order to adapt a given size roller support for installation on doors having different floor clearances, the roller mounting in the support should be adjustable. It is, therefore, another object of the invention to provide novel means to facilitate easy adjustment of the yieldable roller mounting.

Another object of the invention is to provide a roller support for a door which is durably constructed, efficient in operation, and not expensive to manufacture or to install.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

Fig. 1 is a front elevational view of the door support mounted upon a door and showing a portion of the housing cover broken away.

Fig. 2 is a vertical central sectional view of the door support.

Fig. 3 is a horizontal sectional view, taken on line 3—3 of Fig. 1.

Referring to the accompanying drawings, the support is shown mounted upon the foot of the free vertical edge of a door 11. It is to be understood that this door is of a kind that is hingedly mounted along its opposite vertical edge so

2

as to be swingably moved into open and closed positions. The door support includes a cast housing 12 having a back wall 13, a top wall 14, a bottom 15, and connecting side walls 16. The back wall 13 extends beyond the top and bottom walls to define mounting flanges 17, each of which is suitably apertured to receive therethrough mounting screws 18 whereby the housing may be secured firmly to the face of the door 11. The bottom wall 15 has a boss 19 formed integral therewith which extends inwardly from said wall and is provided with a square or non-circular vertical passage 21 opening onto the bottom face of the housing 12.

15 An inverted U-shaped bracket or yoke 22 provides a mounting for a roller 23 which is suitably journaled therein preferably by means of a bolt 24 extending through said roller and through aligned apertures in the sides 25 of said bracket.

20 The intermediate or bight portion 26 of the bracket 22 has a square or non-circular shank 27 formed integral therewith extending outwardly therefrom. The shank 27 is of a size and shape to be slidably received within the non-circular passage 21 of boss 19 in the manner shown.

The top wall 14 of the bracket 12 is provided with a boss 28 on its inside face. This boss has an aperture 29 in axial alignment with the vertical passage 21 in boss 19. A bolt 31 has its shank 32 extended downwardly through the boss 28.

30 The head of said bolt preferably is seated on a washer 33 laid against the top face of the top wall 14. A substantial portion of the bolt shank 32 is threaded, as at 34, and this threaded portion is screwed into a tapped hole 35 in the shank 27.

35 It should be quite evident that upon rotation of the bolt 31 in either direction the shank 27 is drawn into or urged outwardly from the housing 12. This affords means whereby the position of the roller 23 may be adjusted relative to the housing 12 after the same has been mounted upon the door 11.

Means is provided whereby the roller 23 and its mounting bracket 22 are resiliently supported in any position of adjustment determined by manipulation of the bolt 31. To this end, a nut 36 is threaded onto the bolt 31 prior to its being threaded into the shank 27. This nut supports the washer 37 having seated thereagainst one end 45 of a tension spring 38. The other end of the tension spring 38 bears against a washer 39 arranged on the bottom face of the boss 23. Manipulation of the nut 36 will increase or decrease the tension of the spring 38 and thereby increase or decrease 50 the resiliency of the mounting. If desired, a lock

nut 41 may be associated with the nut 36 to prevent inadvertent displacement of the nut 36 after it has been adjusted on the threaded shank 32.

The housing 12 is provided with a cover 42 which overlies the entire front face thereof and which may be secured in place as by screws 43. Should adjustment of the spring tension become necessary, or in the event of part replacement, the cover 42 may be easily and quickly removed to thereby expose the spring, nut and bolt assembly.

Although an exemplary form of the invention has been disclosed in the accompanying drawings, and described in detail in the foregoing specification, it should be understood that the invention is capable of embodying a variety of modifications in its detail structure without departing from the spirit of the invention or the scope of the appended claim.

I claim:

An adjustable door support of the character described comprising in combination a housing including side walls, a top wall and a bottom wall, means to facilitate mounting of the housing on a door, a boss on and projecting downwardly from the bottom face of the top wall, said top wall and boss having an opening therethrough, a boss on and projecting upwardly from the top face of the bottom wall, said bottom wall and the last named boss having a square opening therethrough in alignment with the opening in the top wall and the first named boss, a roller bracket having a square shank extending upwardly

through the square opening, a tapped opening in the free end of said shank, a headed adjusting bolt extending downwardly through the opening in the top wall and the top wall boss and threaded into the tapped opening, the bolt head resting normally against the top face of the top wall, a nut on the bolt within the housing, a compression spring on said bolt, said spring being confined between the bottom face of the top wall boss and the nut, said nut being adjustable so that the spring tension may be varied upon adjustment of the nut, a front wall on the housing removable to admit access to the nut for adjusting the same, and a roller carried by said bracket adapted to ride along a surface to support a door upon which the device is mounted.
